Specification for Design.

Patented July 28, 1914.

Application filed May 29, 1914. Serial No. 841,919. Term of patent 14 years.

To all whom it may concern:

Be it known that I, CLARA L. MEAD, a citizen of the United States, residing at Rahway, in the county of Union and State of New Jersey, have invented a new, original, and ornamental Design for a Paper Sheet or Similar Article, of which the following is a specification, reference being had to the accompanying drawing, forming part thereof.

The figure is a plan view of a paper sheet showing my new design.

The design is a wood or grove with a winding path and owls perched in the trees. In the background is a sky of contrasted

color, preferably red as indicated, against which the trees are silhouetted. There is a moon in the sky; and specters, or ghostly figures, shrouded and with death's heads, are moving among the trees.

I claim:

The ornamental design for a paper sheet or similar article, substantially as shown.

Signed by me at Rahway, New Jersey, this 25th day of May, 1914.

CLARA L. MEAD.
